US00D743510S

(12) **United States Design Patent**
Lombardi, III

(10) **Patent No.:** **US D743,510 S**
(b4) **Date of Patent:** **** Nov. 17, 2015**

(54) **HIGH PRESSURE FLUID CONDUIT
CONNECTOR COMPONENTS AND
CONNECTOR ASSEMBLY**

(71) Applicant: **Nordson Corporation**, Westlake, OH (US)

(72) Inventor: **Francis J. Lombardi, III**, Erie, CO (US)

(73) Assignee: **Nordson Corporation**, Westlake, OH (US)

(**) Term: **14 Years**

(21) Appl. No.: **29/476,030**

(22) Filed: **Dec. 10, 2013**

Related U.S. Application Data

(63) Continuation-in-part of application No. 14/068,703, filed on Oct. 31, 2013.

CLAIM

The ornamental design for a high pressure fluid conduit connector components and connector assembly therefor, as shown and described.

DESCRIPTION

FIG. 1 is a top front isometric view of the high pressure fluid conduit connector components and connector assembly;

FIG. 2 is a bottom rear isometric view of the high pressure fluid conduit connector components and connector assembly; FIG. 3 is a front view of the high pressure fluid conduit connector components and connector assembly; FIG. 4 is a rear view of the high pressure fluid conduit connector components and connector assembly; FIG. 5 is a right side view of the high pressure fluid conduit connector components and connector assembly; FIG. 6 is a left side view of the high pressure fluid conduit connector components and connector assembly; FIG. 7 is a top view of the high pressure fluid conduit connector components and connector assembly; FIG. 8 is a bottom view of high pressure fluid conduit connector components and connector assembly; FIG. 9 is a top cross sectional view of the high pressure fluid conduit connector components and connector assembly, taken along line 9-9 in FIG. 1 and generally along the center of the high pressure fluid conduit connector components and connector assembly; FIG. 10 is a top cross sectional view of the high pressure fluid conduit connector components and connector assembly, taken along the line 10-10 in FIG. 1 and generally below a center of the high pressure fluid conduit connector components and connector assembly; FIG. 11 is a top front isometric exploded view of the high pressure fluid conduit connector components and connector assembly, with two fluid connector components disengaged from one another; and, FIG. 12 is a bottom rear isometric exploded view of the high pressure fluid conduit connector components and connector assembly. The broken line showing is included for the purpose of illustrating portions of the article and forms no part of the claimed design.
